UNITED STATES PATENT OFFICE.

CHARLES F. KIESER, OF COLUMBUS, OHIO, ASSIGNOR TO THE SEAGRAVE COMPANY, OF COLUMBUS, OHIO, A CORPORATION OF OHIO.

AERIAL LADDER.

1,081,122.

Specification of Letters Patent.

Patented Dec. 9, 1913.

Application filed February 7, 1911. Serial No. 607,143.

To all whom it may concern:

Be it known that I, CHARLES F. KIESER, citizen of the United States, residing at Columbus, in the county of Franklin and 5 State of Ohio, have invented a certain new and useful Improvement in Aerial Ladders, of which the following is a specification.

This invention relates to a ladder of the kind shown in the patent to Frederic S. 10 Seagrave, No. 865,951 dated September 10, 1907, but in the present invention the ladder is automatically raised; and one of the objects of the invention is to provide devices for locking the ladder in its lowered position 15 said devices being conveniently operated for releasing the ladder to permit the operation of the automatic raising means.

Other objects will appear from the following description and claims.

20 The invention is embodied in the construction herein shown and described and then particularly pointed out in the claims.

In the accompanying drawing—Figure 1 is a side elevation of the lower portion or 25 foot of the ladder showing the same in lowered and locked position. Fig. 2 is a similar view showing the same elevated. Fig. 3 is a central longitudinal section of one of the spring cylinders and the spring of the 30 elevating mechanism. Fig. 4 is a plan view which includes two of the cylinders shown in Fig. 3. Fig. 4^a is a detail plan view of the clutching and catching devices.

In the views 5 designates the ladder proper which is of the usual or any approved construction but which is fulcrumed near its foot or forward end by means of trunnions at 5^a in brackets or standards 6 secured upon a turntable 7. Secured on 35 said turn table is a pair of cylindrical casings 8, 8, containing a piston-like head 9 having a rod 10 that extends rearward through the rear end of the cylinder where it is provided with an eye 10^a. The forward 40 end of each of the piston-like heads is provided with a powerful spring 11 that urges the rod forward and the rear end of the casing is provided with a spring 11^a, somewhat separated from the head 9 when the 45 spring 11 is compressed by the lowering of the ladder. A cross bar 12 connects the two rods 10 by being passed through the eyes 10^a and the opposite outer ends of the cross bar 12 are pivotally connected by means of 50 rods 12^a with the apices of angular brackets

13 projecting from the lower side (Fig. 1) of the lateral timbers of the ladder. On the turntable 7, forward of the foot of the ladder, is a standard 14 having a bearing 15 in which is journaled a shaft 16 having laterally extending short arm 17 and a handled arm 18. Hinged to the short arm 17 is a rod 19 that reaches rearwardly and downwardly to and through a guide bearing 20 secured between the two spring casings 8. 60 On the lower end of the rod 19 is hinged a pair of toggle links 21 having their free ends connected with the shanks of a pair of clamping jaws 22 that are pivoted together at 23. These clamping jaws are so formed, 65 and located and the links operating them are so connected with the rod 19 and jaw shanks that when the ladder is prone the jaws can grip the bar 12 and the ladder be locked in the prone position. This locking effect is 70 obtained by turning the handle lever 18 down from the position seen in Fig. 2 to the position seen in Fig. 1 and securing said handle lever in the stirrup 24 secured on the adjacent standard 6, a pin 24^a being inserted through holes in the stirrup arms 75 above the lever to prevent the latter from rising.

35 designates a coil spring located on the rod 19 between the bearing 20 and a collar 19^a to urge the jaws to open position when the rod 19 is slightly raised from locking position.

Swiveled in a nut 25 journaled at 25^a at the upper end of the standard 14 is a screw 90 26, of high pitch and journaled at 27^a in suitable brackets 27 in the upper side of the ladder is a nut 28 that travels on the screw 26. The screw has fixed on it at its forward end a miter gear 29 that is engaged by a 95 pinion 33 on a shaft 31. The shaft 31 can be rotated by a suitable crank to turn the screw 26 and the screw can be locked from rotation by means of a dog 32 engaging a suitable clutch member 33 on the shaft. The 100 clutch member and co-operating parts constitute the subject of another application for patent.

In practice it is proposed that the springs 11 shall be powerful enough to automatically move the ladder to elevated position 105 when the cross bar 12 is released. Where the springs 11 are of a power sufficient to alone elevate the ladder against the screw 26 that member is turned and serves as a 110

retarder but not alone as a lock to hold the ladder. The elevating operation can be intelligently controlled by means of a suitable brake device operated by a lever 34 properly mounted to operate a brake or clutch member to apply friction to retard, or stop either the elevating or lowering operation. The ladder is, of course, depressed to prone position by turning the screw 26 in a direction opposite that in which it turns when the ladder is raised.

What I claim is:

1. In a ladder of the kind described, the combination with the ladder proper, of a fulcrum on which the same can be elevated, a screw 26, a nut on the ladder to engage said screw, a spring of a strength adapted to operate on the ladder to automatically move the same to elevated position notwithstanding the engagement of said nut with the screw, means for turning said screw to depress the ladder, means for locking the ladder in prone position, and means independent of the said locking means for locking the ladder in other positions.
2. In a ladder of the kind described, the combination with the ladder proper, a fulcrum on which the same can be elevated, a pair of springs, plunger rods operated by the springs, a bar connecting the plunger rods, link rods connecting said bar with the ladder, and means for engaging said bar to lock the ladder in prone position including a pair of gripping jaws, a rod for operating

the same to grip said bar to lock the ladder in prone position, means for operating said rod, and means for locking said last named means.

3. In a ladder of the kind described, the combination with the ladder proper, a fulcrum on which the same can be elevated, a pair of springs, plunger rods operated by the springs, a bar connecting the plunger rods, link rods connecting said bar with the ladder, and means for engaging said bar to lock the ladder in prone position including a pair of gripping jaws, a rod for operating the same to grip said bar to lock the ladder in prone position, means for operating said rod in one direction to close the jaws and a spring for urging said rod to open the jaws.

4. In a ladder of the kind described, the combination with the ladder proper and a fulcrum on which the same can be elevated, a screw 26, a nut on the ladder to engage said screw, and means adapted to operate on the ladder to elevate the same and automatically cause the nut to move longitudinally on the screw, means for positively depressing the ladder, means for locking the ladder in prone position and means independent of said locking means for locking the ladder in other positions.

CHARLES F. KIESER.
